UNITED STATES PATENT OFFICE

HENRY B. SHERIDAN, OF CLEVELAND, OHIO, ASSIGNOR TO THE SHERIDAN ELECTRIC LIGHT COMPANY, OF NEW YORK, N. Y.

ELECTRIC LAMP.

SPECIFICATION forming part of Letters Patent No. 259,224, dated June 6, 1882.

Application filed January 26, 1882. (No model.)

To all whom it may concern:

Be it known that I, HENRY B. SHERIDAN, of Cleveland, in the county of Cuyahoga and State of Ohio, have invented certain new and 5 useful Improvements in Electric Lamps, of which the following is a full, clear, and exact description.

Reference is to be had to the accompanying drawings, forming part of this specification, in 10 which similar letters of reference indicate corresponding parts in all the figures.

Figure 1, Sheet 1, is a side elevation of my improvement, the base-plate and casing being shown in section through the line $x-x$, Fig. 2. 15 Fig. 2, Sheet 1, is a plan view of the same, the casing being shown in section through the line $y-y$, Fig. 1. Fig. 3, Sheet 2, is a side elevation, partly in section, showing my improvement applied to a lamp with carbons meeting in a 20 vertical line. Fig. 4, Sheet 2, is a side elevation, partly in section, showing my improvement applied to a lamp with carbons meeting at an angle.

The object of this invention is to provide an 25 improved regulating mechanism for electric lamps, by means of which a steadier light will be produced than has heretofore been attained, and also by means of which the distance of the arc will be positively fixed.

30 The invention consists in the combination, with the lever, carrying armatures and interposed between low-resistance electro-magnets and high-resistance electro-magnets, and a toothed wheel rigidly connected with a cone- 35 pulley carrying the carbon-supporting chains, of a pivoted connecting-bar and a lever fulcrumed to a spring and having a fixed pawl, whereby the passage of an electric current through the coils of the low-resistance magnets 40 will separate the carbons to form the voltaic arc; also, in the combination, with the above-mentioned elements, of a second pivoted connecting-bar and a lever fulcrumed to a spring and having a pivoted pawl, whereby the passage 45 of an electric current through the coils of the high-resistance magnet will move the carbons toward each other after being separated by combustion; and, also, in the combination, with the armature-carrying lever interposed be- 50 tween the low-resistance coils and the high-resistance coils, the connecting-bar, and the

suspended lever, of a spiral spring and its adjusting-screw, whereby the resistance of the armature-carrying lever to the action of an electric current passing through the coils of 55 the low-resistance magnet is regulated, as will be hereinafter fully described.

A represents a plate, to which is secured a U-shaped or arched frame, B.

To the upright arms of the frame B, and directly opposite each other, are attached the low-resistance magnet-coils C and the high-resistance magnet-coils D. The ends of the magnets of the coils C and D are concaved upon the arc of a circle to correspond with the arc 65 of the curved armatures C' D', which are attached at their middle parts to the opposite ends of the slightly-bent balancing-lever E. The balancing-lever E is pivoted at its angle to the upper end of the standard F by a screw, 70 G. The lever E is bent to hold the armatures C' D', so that their position relative to their respective magnets and to each other will be such that when one of the armatures is centrally located in respect to the magnetic field 75 of its magnet the other armature will be upon the edge of the magnetic field of its magnet, in position to be acted upon when the power of its magnets preponderates. The lower end of the standard F is attached to the base- 80 plate A.

To the standard F, below the lever E, is pivoted the shaft I, to which is attached the double or cone pulley H and the notched or toothed wheel K, so that the said pulley and wheel will 85 be rigidly connected.

To the larger part of the cone-pulley H is attached and around it is wound the chain L', that carries the positive carbon.

To the smaller part of the cone-pulley H is 90 attached and around it is wound in the opposite direction from the chain L' the chain L, that carries the negative carbon.

To the arm of the lever E, next the high-resistance magnet-coils D, and at a little distance from the pivot of said lever, is pivoted the upper end of the connecting-bar M, and to the other arm of the lever E, but at a greater distance from its pivot, is pivoted the upper end of the connecting-bar N.

To the lower end of the connecting-bar M is 95 pivoted the end of a lever, O, which is ful-

crummed at its other end to the lower end of a spring, P. The upper end of the spring P is secured to the frame B or to a support attached to the said frame. The lower end of 5 the connecting-bar N is pivoted to the lever Q at a little distance from its inner end. The outer end of the lever Q is fulcrumed to the lower end of a spring, R, the upper end of which is attached to the frame B or to a support secured to the said frame.

To the inner end of the lever Q is pivoted a pawl, S, which rests against and engages with the teeth of the wheel K, and to the side of the lever O is attached, or upon it is formed, a pawl, 15 S', which rests against and engages with the teeth of the wheel K upon the opposite side of the said wheel from the pawl S, as shown in Fig. 1.

The coils of the low-resistance magnet C are 20 connected with the positive binding-post V by the wire W and with the holder of the positive carbon by the wire X. The holder of the negative carbon is connected with the negative binding-post V' by the wire Y. The coils 25 of the high-resistance magnet D are connected with the positive binding-post V by the wire Z and with the negative binding-post V' by the wire a, either directly or by connecting the said wire a with the wire Y. The latter 30 arrangement is shown in Fig. 1. With this construction, when an electric current passes through the coils of the low-resistance magnet C the armature C' is attracted in the direction of arrow 1, turning the lever E upon its fulcrum and raising the lever O, which upward movement of the lever O causes the pawl S' to turn the wheel K in the direction of arrow 3, unwinding the chain L, winding up the chain L', and thus separating the carbons sufficiently 35 to form the voltaic arc. When the carbons become so widely separated by consumption that the electric current cannot pass, then the entire current passing over the coil of the high-resistance magnet D causes the magnet 40 to attract the armature D' in the direction of arrow 2, moving the lever E upon its fulcrum and raising the lever Q. The upward movement of the lever Q causes the pawl S to turn the wheel K in the direction of arrow 4. On 45 account of the connecting-bar N being pivoted to the lever E farther from its fulcrum than the connecting-bar M, the pawl S of the lever Q will travel faster than the pawl S' of the lever O and cause the wheel K to begin to 50 move before it is released from the pawl S', which is held against the said wheel K by the spring P, and thus acts as a holding-pawl. The resistance of the lever E to the action of the 55 electric current upon the armature C' is regulated by the spiral spring T, the upper end of which is attached to the lever O. The lower

end of the spring T is attached to the forward end of the screw U, which passes up through a screw-hole in the base-plate A, so that the tension of the spring T can be regulated by 65 adjusting the screw U. The screw U is secured in place, when adjusted, by a jam-nut, U'.

Having thus fully described my invention, I claim as new and desire to secure by Letters Patent—

1. In an electric lamp, the combination, with 70 the lever E, carrying the armatures C' D', and interposed between the low-resistance coils C and the high-resistance coils D, and the toothed wheel K, rigidly connected with the cone-pulley H, carrying the carbon-supporting chains L L', of the pivoted connecting-bar M and the lever O, fulcrumed to a spring, P, and having a fixed pawl, S, substantially as herein shown and described, whereby the passage of an electric current through the coils of the low-resistance magnet will separate the carbons to form the voltaic arc, as set forth.

2. In an electric lamp, the combination, with 85 the lever E, carrying the armatures C' D', and interposed between the low-resistance coils C and the high-resistance coils D, the toothed wheel K, rigidly connected with the cone-pulley H, carrying the carbon-supporting chains L L', the pivoted connecting-bar M, and the lever O, fulcrumed to the spring P and having fixed pawl S', of the pivoted connecting-bar N and the lever Q, pivoted to a spring, R, and having a pivoted pawl, S, 90 substantially as herein shown and described, whereby the passage of an electric current through the coils of the high-resistance magnet will move the carbons toward each other after being separated by combustion, as set forth.

3. In an electric lamp, the combination, with 95 the lever E, carrying the armatures C' D', and interposed between the low-resistance magnet C and the high-resistance magnet D, 105 the connecting-bar M, and the lever O, of the spiral spring T and its adjusting-screw U, substantially as herein shown and described, whereby the resistance of the lever to the action of the electric current passing through the low-resistance coils is regulated, as set forth.

4. In an electric lamp, the curved armatures C' D' and the bent lever E, to which they are attached, in combination with the high and 110 low resistance magnets C D, having concaved ends for operating the arc-regulating mechanism, substantially as specified.

HENRY B. SHERIDAN.
